219,706

COMBINED BOTTLE AND DISPENSING CLOSURE THEREFOR

Albert J. Elias, Greenwich, Conn., assignor to Schering
Corporation, Bloomfield, N.J., a corporation of New
Jersey

Filed Sept. 26, 1969, Ser. No. 19,301

Term of patent 14 years

Int. Cl. D9—01

U.S. Cl. D9—63

FIG. 1 is a perspective view of a combined bottle and dispensing closure therefor embodying my new design;

FIG. 2 is an enlarged top plan view of FIG. 1 with the closure removed;

FIG. 3 is an enlarged front elevational view of FIG. 2;

FIG. 4 is a side elevational view of FIG. 3 looking from the left;

FIG. 5 is a rear elevational view of FIG. 3; and

FIG. 6 is a front perspective view of FIG. 3.

I claim:

The ornamental design for a combined bottle and dispensing closure therefor, as shown.
